UNITED STATES PATENT OFFICE.

MILLIE NOTTAGE, OF CAIRO, ILLINOIS.

DESIGN FOR A GAME-BOARD.

SPECIFICATION forming part of Design No. 24,384, dated June 11, 1895.

Application filed May 14, 1895. Serial No. 549,322. Term of patent 7 years.

To all whom it may concern:

Be it known that I, MILLIE NOTTAGE, a citizen of the United States, residing at Cairo, in the county of Alexander and State of Illinois, have invented a certain new and original Design for a Game-Board, of which the following is a specification.

The design consists of the novel ornamentation for a game board, as hereinafter set forth and illustrated in the accompanying drawing.

The said drawing is a plan view of a game-board made in accordance with my invention.

The drawing shows a board of an oblong rectangular shape, having upon its surface a succession of spaces, forming a continuous path which path pursues a labyrinthine course consisting of a number of straight lines formed by a number of curves and angles along said course, some of which angles are right angles, while others of which angles are either less than or greater than right angles. At one point on the course a circular figure is shown, which circular figure is divided into a number of spaces arranged radially around a smaller circle within its center.

Near one corner of the board, and directly in the course of the path, is shown a figure representing a perspective view of the front of a shed or house having a doorway from which the course is represented as starting.

A rectangular space is left at one side of the center of the board, in which space appropriate words indicating the name of the game, &c., may be printed or stamped. On any one or more of the said spaces which combine to form this continuous course, appropriate words or symbols may be printed or stamped, as directions to the players, for the purposes of carrying out the game. Appropriate words or symbols may also be printed or stamped upon the said figures.

Suitable ornamentations or coloring may be used upon the surface of the board.

In the drawings, A designates the house or shed, having a doorway a.

B designates the path formed by the succession of adjacent spaces b.

C designates the circular figure having radial spaces c; and D designates the rectangular space in which may be printed or stamped the words or symbols indicating the name of the game.

I claim as my invention—

The design for a game board, substantially as herein shown and described.

In testimony whereof I affix my signature in presence of two witnesses.

MILLIE NOTTAGE.
